Application August 31, 1934, Serial No. 742,214

8 Claims. (Cl. 293—55)

This invention has to do with bumpers for automobiles.

It is an object of this invention to provide an improved bumper construction comprising a pair of impact bars arranged one ahead of the other.

It is another object of the invention to provide an improved bumper construction including a pair of identical impact bars arranged one ahead of the other and so as to provide a generally 10 shutter-like effect.

It is a further object of the invention to provide a bumper construction comprising a pair of similar impact bars arranged so that they are bowed in intersecting planes.

15 It is a further object of the invention to provide improved intermediate and end bumper connections.

It is a further object of the invention to provide an improved bumper construction embodying similar or substantially identical impact bars 20 arranged so that one of the bars serves as a means for cushioning and supporting the other bar.

It is also an object of the invention to provide a bumper of shutter-like formation including 25 combined ornamental and reinforcing instrumentalities for connecting the bars together.

In accordance with the general features of the 30 invention, the impact bars may be identical. Each is formed to extend substantially across the vehicle and may be concavo-convex in cross section and is preferably bent edgewise and longitudinally transverse to its edges. The bars are placed one ahead of the other and preferably bowed in different planes so that one of the bars 35 is dipped relative to the other bar. This arrangement of the rear bar may be brought about by rotating one bar relative to the other about an axis passing through the ends of the bar, so that when so rotated a large impact area is provided by the combined bars, the area being preferably greatest at the center and reduced at the 40 ends. The bars may be substantially uniformly spaced or may be closer at one point than at another.

45 The ends of the respective bars are preferably secured together in slightly spaced relation.

Intermediate connections for the bars may also be provided, as well as means for attaching the connected bars to the frame horns or other appropriate parts of the automobile.

50 The bars are preferably of spring steel and relatively yieldable between the places where they are connected together.

The improved bumper construction afforded by the present invention is extremely simple since

it involves a minimum of parts which are readily assembled, and which are formed by inexpensive operations, thus lending itself to economical construction.

Other objects and advantages of the invention 5 will appear as the description proceeds.

This invention (in preferred forms) is illustrated in the drawings and hereinafter more fully described.

On the drawings:

Figure 1 is a plan view of a bumper embodying the invention.

Figure 2 is an elevational view of the bumper construction shown in Figure 1.

Figure 3 is an enlarged fragmentary sectional 15 view taken substantially in the plane designated by the line III—III in Figure 2, looking in the direction of the arrows.

Figure 4 is an enlarged sectional view taken substantially in the plane designated by the line 20 IV—IV in Figure 2, looking in the direction of the arrows.

Figure 5 is a bottom plan view of the mounting bracket of Figure 4, rotated 90° counter-clockwise.

Figure 6 is a fragmentary elevational view 25 similar to the right end portion of Figure 2 but showing a modified form of end bracket.

Figure 7 is an enlarged sectional view taken substantially in the plane designated by the line 30 VII—VII in Figure 8, looking in the direction of the arrows.

Figure 8 is a fragmentary sectional view taken substantially as indicated by the broken line 35 VIII—VIII in Figure 7.

Figure 9 is a plan view of a further modified 40 form of the invention.

Figure 10 is an elevational view of the construction appearing in Figure 9.

Figure 11 is an enlarged sectional view taken substantially in the plane designated by the line 45 XI—XI in Figure 10, looking in the direction of the arrows.

Figure 12 is an enlarged sectional view taken substantially in the plane designated by the line XII—XII in Figure 10, looking in the direction of the arrows.

Figure 13 is a fragmentary plan view similar to the left end of Figure 1 but showing a modified 50 form of the invention.

Figure 14 is an enlarged fragmentary sectional view taken substantially in the plane designated by the line XIV—XIV in Figure 13.

Figure 15 is a horizontal sectional view through the axis of the spacer element appearing in Figure 13, looking downwardly.

- Figure 16 is an enlarged sectional view of the spacer element, taken substantially in the plane designated by the line XVI—XVI in Figure 13, looking in the direction of the arrows.
- 5 Figure 17 is a view similar to Figure 13 but of a still further modified form of the invention.
- Figure 18 is an elevational view of the structure appearing in Figure 17.
- Figure 19 is an enlarged isometric view of the 10 spacer elements appearing in Figures 17 and 18.
- Figure 20 is an enlarged fragmentary sectional view taken substantially in the plane designated by the line XX—XX in Figure 18, looking in the direction of the arrows.
- 15 Referring now more particularly to the drawings, one form of the invention comprises essentially front and rear bars 1 and 2, end connecting brackets 3 and intermediate connecting and reinforcing brackets 4.
- 20 The bars 1 and 2 may be different as will appear hereinafter, or identical as shown, each consisting of a spring strip of steel or other suitable material and concavo-convex in cross section and arranged, when in operative assembly, with its convex face in a position to receive impacts. Each bar is formed with an edge bend so as to dip with respect to the extremities of the bar and is bowed forwardly so that its ends extend rearwardly with respect to its central portion. Each bar is moreover formed so that when mounted in impact receiving position, its lower edge is substantially foremost, as seen at 5.
- By turning one of the bars such as the bar 2 about a horizontal axis which, for example, passes through the upper end corners 6 of the bar, to a sufficient degree, the upper and lower edges 7 and 5 of said bar may be disposed in horizontal planes. When the bar 2 is arranged in parallelism with the bar 1 and to the rear thereof and is then 40 turned as mentioned, the lower edge 5 of the rear bar is caused to move forwardly as well as upwardly, and the upper edge 7 is caused to move rearwardly as well as upwardly, with respect to the front bar. As a result of this 45 turning of the rear bar, the vertically projected distance between the edges of the back bar 2 is less than the corresponding distance between the edges of the front bar 1. Viewed in front elevation as in Figure 2, it will be observed 50 that when the bars 1 and 2 are assembled after the said turning of the rear bar 2, their upper edges 8 and 7, respectively, are substantially flush at the ends of the bumper and the rear bar 2 projects upwardly shutter-like beyond the front bar 55 1 in a gradually increasing degree from the ends toward the center of the bumper.
- To the end that the extremities of the bars 1 and 2 may be connected, each end bracket 3 is provided with a base 9 from which extend on one 60 side thereof walls 10 and 11 having convex surfaces 12 and 13, respectively, formed in such a shape as to fit preferably in nested relation against the concave surfaces of the respective bars 1 and 2. The walls 10 and 11 are bored at 65 14 and 15, respectively, so that the bores are preferably in axial alinement. The bores are preferably also at substantially right angles to the portions of the wall through which they pass, and accordingly it will be observed that the bore 70 14 is disposed at a higher level than the bore 15. The end portions of the bars 1 and 2 are similarly bored at 16 and 17, respectively, the bore 16 being arranged closer to the upper edge 8 of the bar 1 and the bore 17 being correspondingly located nearer the bottom edge 5 of the rear bar 2.

When the bore 16 of the bar 1 is registered with the corresponding bore 14 of the wall 10 a bolt 18 is passed rearwardly therethrough, receives a lock washer 19 and a tightening or clamping nut 20, the depth of the wall 10 being sufficient to accommodate the same. Likewise, the rear bar 2 is bolted to the wall 11 of the bracket or connector 3.

It is to be observed that the bracket 3 is formed to provide flanges 21 extending forwardly at the 10 upper and lower extremities of the front face of the wall 10 for engagement with the upper and lower end edge portions of the front bar 1. It will also be noted that the walls 10 and 11 are connected at their upper and lower ends by wall 15 portions 22 and 23 which cooperate with the rear wall 11 to provide flanges engageable with the upper and lower end edges of the rear bar 2.

The upper and lower walls 22 and 23 are extended rearwardly beyond the transverse wall 11 20 and are preferably reduced so as to substantially merge with the base 9 of the bracket 3 at the rear of the bracket as shown at 24. This feature gives the bracket as a whole a streamline effect, which is enhanced in view of the bracket's being of substantially greater height at its forward end and of gradually reduced height rearwardly.

With the brackets 3 bolted to the ends of the bars 1 and 2 assembled in the relation illustrated and described, a complete bumper capable of being attached in any desirable manner to the frame of the automobile is provided. Such a bumper may be attached to the frame or chassis of the automobile by brackets attached only to the rear bar 2, providing great flexibility between the bars 1 and 2 throughout their length. If desired, however, the bars 1 and 2 may be reinforced and clamped together intermediate the end brackets 3 by means which may serve also to mount the bumper structure directly on the frame or chassis. In the latter event, a structure such as that to be described presently and illustrated in the drawings may be employed.

One form of clamping device is illustrated at 4 and comprises a bracket which may be given 45 any suitable ornamental design such as that shown. The bracket 4 has a web 25 arranged to extend in a generally vertical plane between the portions of the bars 1 and 2 to be connected thereby, said web terminating forwardly in a 50 flange 26 which has a front face of a curvature such as to nest against the rear face of the front bar 1. The bracket 4 extends substantially above and below the bars so as to provide a means for preventing another bumper from riding over 55 and interlocking with the bumper forming the subject matter of the invention.

The portion of the web 25 behind the impact section 1 is formed as a sleeve boss 27 which extends generally at right angles to the adjacent 60 portion of the flange 26. Substantially midway of the upper and lower edges of the impact section 1, the latter is provided with a bolt hole 28 which, when in register with the bore of the sleeve 27, receives the shank of a clamping bolt 65 29. A lock washer 30 and nut 31 applied to the rear end of the bolt 29 and tightened up against the sleeve 27 cooperate with the head of the bolt in securely clamping the bumper bar 1 to the front of the bracket 4.

The rear part of the web 25 adjacent the rear bar 2 terminates in a flange 32 whose rear face is of such curvature as to fit and nest against the front surface of the rear bar 2. The web 25 is provided between the flanges 26 and 32 with a 75

second sleeve boss 33 arranged so that its bore will register with a bore or hole 34 substantially midway of the upper and lower edges 1 and 5, respectively, of the rear bar 2. The boss 33 is 5 preferably arranged at substantially right angles to the adjacent flange portions 26 and 32, and to the adjacent part of the rear bar 2.

To the end that the bumper structure may be fastened to a suitable support such as a frame 10 horn 35 of the automobile, there is provided an attaching bracket 36 of any suitable form. In the illustrated embodiment of the invention, the bracket 36 has a rear wall 37 formed to engage the front of the horn 35 and be bolted thereto 15 at 38. The bracket 36 is open lowermost and has sidewalls 39 and a top wall 40 and a preferably flat front wall 41. The sidewalls 39 extend forwardly beyond the front wall 41 so as to space the latter from the rear bar 2, the forward ends 20 of the walls 39 being curved as shown at 42 so as to conform to the curvature of the rear side of the bar 2. By thus spacing the front wall 41 rearwardly of the bar 2, said wall 41 may be made flat and is arranged at substantially right 25 angles to the bracket sleeve 3 and back bar bore or hole 34, and is itself provided with a bolt hole 43 adapted to be placed in register with the bore of the sleeve 33 and the bore 34.

It is now evident that with the various bores 30 just mentioned in axial alignment, a clamping bolt 44 with its head resting against the bracket flange 26 may be extended rearwardly through the bracket sleeve 33, rear bar 2 and front wall 41 of the frame horn bracket 36 and, with a lock 35 washer 45 and nut 46 applied to the free end of the shank of the bolt 44, the bracket 4, rear bar 2 and bracket 36 are rigidly clamped together.

A similar arrangement may be provided for the 40 other frame horn 35 so as to provide a mounting upon each horn for the bumper.

The side and top walls of the bracket 36 as 45 well as the forward curved extensions of the side walls provide suitable reinforcement for the bracket 36. The mountings at the brackets 36 and 4 provide therebetween in effect a central impact zone A affording a yieldable structure supported at its ends, and end zones B in the form of resilient cantilevers.

If desired, the bumper may be supported in any 50 other suitable manner, either at the ends or intermediate the ends, from the automobile frame or chassis.

By arranging each of the bars with its lower 55 edge substantially foremost and its upper edge substantially rearmost, any generally horizontal impact upon each of the bars is in effect resolved in a substantially bending and twisting or torque stress enabling each bar to offer increased resistance to such impacts. Moreover, the arrangement possesses a generally streamline effect 60 which is advantageous from an air resistance standpoint. In addition, the structure is such as to afford an increased impact area from the center toward the ends of the bumper.

It will be noted that with the bolt holes 14 and 15 in the walls 10 and 11 of each end bracket in axial alignment with each other, said bores may be drilled or otherwise formed by a single 65 operation.

If desired, instead of employing two bolts for the ends of the bars 1 and 2 in conjunction with end bracket 3, the bracket could be formed with a spacing portion to be positioned between the ends 70 of the bars 1 and 2, and a single bolt passed

through the ends of the bars 1 and 2 and the intervening spacing portion of the bracket 3.

It will be understood that the ends of the bars as well as the intermediate portions may be joined in ways other than those illustrated and 5 described, the latter being presented for purposes of illustration only.

It is to be noted that the spaced bumper engaging ends 42 of the walls 39 of the mounting brackets 36 are of different depth. The reason 10 for this becomes evident upon viewing Figure 1, the bumper bar 2 at each bracket 36 being inclined to end wall 37 of such bracket longitudinally of the bumper, while the front wall 41 of said bracket is not so inclined. Rather, the wall 15 41 is arranged to accommodate the bolt 44, which with the bracket 4 extends rearwardly in a substantially vertical plane.

A modified form of end bracket construction 20 is shown in Figures 6, 7 and 8, including a bracket element 47. The element 47 is a hollow body similar to the element 3 previously described, but instead of providing separate walls or ledges against which the respective bars 1 and 2 are positioned, the bracket element 47 is formed with 25 a front recess 48 to accommodate the end of the front bar 1 so as to substantially engage the upper and lower edges of the bar as well as the end edge as shown in Figure 6, and with a preferably cylindrical boss 49 extending rearwardly 30 from the wall of the recess 48. The boss 49 merges with the inner wall 50 of the bracket body 47, and terminates rearwardly in a plane inclined upwardly and rearwardly to accommodate the front face of the rear impact bar 2 as clearly 35 seen in Figure 7. The boss 49 preferably does not extend directly rearwardly, but preferably is arranged in a substantially horizontal plane and extends inwardly in the general direction of the longitudinal axis of the vehicle, as clearly seen 40 in Figure 8. The inner wall 50 of the element 47 is cut away at 51 to provide a generally triangular socket in the said wall 50. Said socket is bounded by a rear generally vertical wall 52, a wall 53 disposed forwardly of the wall 52 and 45 54 forming a hypotenuse of the triangular socket, and an interrupted third wall 54 which does not meet the wall 52 and which extends rearwardly from the wall 53. The wall 53 is shaped to conform to the cross-sectional curvature of the 50 rear bar 2 as clearly seen in Figure 7, and is flush with the rear terminus 49a of the tubular boss 49. The socket 51 is of such size as to readily permit the insertion of the end of the rear bar 2 so that the front surface thereof may be 55 fitted against the wall 53 and terminus 49a of the boss 49, with the upper and lower edges of the bar 2 located respectively at the juncture of the walls 52 and 53 and the juncture of the walls 53 and 54.

The bars 1 and 2 are provided with bolt holes 60 so arranged that when the bars are associated with the bracket element 47 as shown in Figures 6, 7 and 8, said holes are registered with the interior of the tubular boss 49. When this registration is effected, a bolt 55 having its head 56 inclined to the shank 57 so as to fit the forward face of the front bar 1 is assembled with the parts so that the shank of the bolt extends through the front bar 1, boss 49, and rear bar 2. So that 65 the clamping nut may exert the proper clamping force, a washer 58 having a substantially perpendicular rear end face 59 and inclined front face 60 conforming with the rear surface of the rear bar 2 is fitted over the rearwardly projecting end 70 75

61 of the shank 57. A lock washer 62 is fitted against the rear face 59 of the washer 58, and then the clamping nut 63 threaded on the end 61 of the shank so as to assemble the ends of the 5 bars 1 and 2 with the bracket element 47 in proper co-operative relation.

It is to be observed that the socket 51 is made sufficiently large to provide clearance not only for the insertion of the end of the rear bar 2 but 10 also for the insertion of the washers and a nut and a wrench for tightening the nut 63.

When the parts are assembled, the front portion of the bracket element 47 is substantially flush with the associated end of the front bar 1, 15 and the end of the rear bar 2 is concealed and protected by the element 47. At the same time, a rigid connection is afforded for the ends of the bars.

A modified bumper and connecting and mounting structure is shown in Figures 9, 10, 11 and 12. This structure involves the provision of a front bar 64 which may be of substantially the same form as either of the bars 1 and 2 previously described. The rear bar 65 of this form of the 25 invention is preferably substantially narrower as shown in Figures 10, 11 and 12. In this form of the invention, the rear bar 65 is arranged in the same general relation to the front bar as is true of the bar 2 previously described, so that the 30 lower edge 66 of the rear bar 65 is disposed slightly below the lowermost portion of the upper edge 67 of the front bar 64. The rear bar in this form of the invention is preferably made substantially narrower than the front bar for the 35 purpose of lightness of construction as well as lowering the cost of materials, the effect from the front being substantially the same as in the form previously described, the rear bar 65 serving both as an impact bar for a considerable area above 40 the front bar 64 and as a cushion member for the front bar. This form of the invention differs from that previously described in other respects, among which is included the spacing of the bars. It will be observed from Figure 9 that the 45 central portions of the bars are closer together than the ends thereof. It is to be appreciated that in the previously described form of the invention, as well as that now being described, the distances between the bars may be varied, and the bars may 50 be secured in parallelism or not as desired. The illustrations are therefore to be considered as exemplary and not as limiting the invention.

A spacer 68 may be provided at the central parts of the bars 64 and 65 to rigidly hold the same in 55 the desired spaced relationship. The spacer member or bracket 68 may be of any desired form whatever, that illustrated having a generally channel shape in cross section with its web 69 foremost and its flanges 70 extending rearwardly. 60 The spacer bracket 68 is preferably formed with a lower tubular boss 71 whose interior registers with an opening in the front bar 64 for the reception of the shank of a bolt 72, the rear protruding end of which receives a lock washer 73 and nut 74 whereby the front bar 64 is rigidly 65 secured to the bracket 68. The web 69 of the bracket 68 at the boss 71 is formed with a front surface shaped to engage the rear surface of the front bar 64 as clearly seen in Figure 11.

70 The flanges 70 of the bracket 68 at the upper part thereof are formed to conform to the front surface of the rear bar 65 so as to clampingly engage the same. Between said portions of the flanges 70, a tubular boss 75 extends rearwardly 75 from the web 69, said boss being closed at the

front by said web. The rear bar 65 is provided with a bolt hole which registers with the interior of the boss 75, the latter being tapped to receive the shank of a clamping stud 76 whose head is separated from the rear side of the rear bar 65 by a washer 77.

The bolts are arranged substantially normal to the adjacent portions of the bars 64 and 65. The bracket 68 is preferably rounded forwardly to provide a pleasing appearance as well as to afford a substantially streamline effect. The bracket 68 also serves to prevent the bumper of another car from locking with the front bar 64, and it will be noted that for this purpose the bracket 68 is provided with a shoulder 78 arranged to engage 15 the upper edge 67 of the front bar 64, the web of the bracket 68 upward from said shoulder forming substantially a continuation of the front face of the front bar 64 as seen in Figure 11.

The flanges 70 are preferably provided with 20 shoulders 79 engageable with the bottom edge 66 of the rear bar 65.

Any suitable means for mounting the bumper bars 64 and 65 on the vehicle may be provided, and for purposes of illustration, spring mounting 25 bars 80 are shown. These bars may be identical and accordingly a description of one will suffice for both. Each bar 80 is formed with a rearwardly disposed portion 81 for attachment to the frame horn or other suitable part of the vehicle, and the inner part 82 of the bar is bent forwardly and then outwardly at its inner end 83 so as to fit against the rear face of the rear bar 65 intermediate the center and an end thereof. The other end 84 of the mounting bar 80 is similarly located with 30 respect to an end 85 of the rear bar 65. The end 83 is secured to the rear bar 65 and both are clamped to the front bar 64 by means including a 35 clamp bracket 86. The end 84 is similarly clamped to the adjacent end 85 of the rear bar 65 and the 40 adjacent end 87 of the front bar 64 by a similar means including a bracket 88. The various brackets 86 and 88 are preferably so associated with the bars 64, 65 and 80 that when they are assembled, the brackets 86 and 88 extend rearwardly in substantially vertical planes. Because of the curvature of the bars 64 and 65 rearwardly and up on opposite sides of their centers, it will be appreciated that the clamping faces of the brackets 86 45 are similarly inclined, and this is also true of 50 the brackets 88. The brackets 86 and 88 are so similar to one another that a description of one of them and the associated bars will suffice for all.

The bracket chosen for description is designated by the reference character 86 and, specifically, 55 appears between the centers and the right ends of the bars appearing in Figures 9 and 10. It will be noted that the brackets 86 and 88 are quite similar to the bracket 4 previously described. They differ, however, in the provision of a shoulder 89 arranged to engage the upper edge 67 of the front bar 64, so that the front surface 90 of the upper part of the bracket is substantially flush with the front surface of the front bar 64. They differ further in providing a rearwardly disposed shoulder 91 for engagement with the lower edge 66 of the rear bar 65.

The brackets 86 and 88 are provided with tubular bosses 92 and 93 for receiving the shank of the bolt 94 and stud 95, respectively, the boss 93 70 being tapped for that purpose and being closed at its front. A nut 96 and lock washer 97 are applied to the threaded end of the bolt 94 to rigidly clamp the front bar to the bracket. To the end 75 that the bars may be mounted on the mounting 75

bar 80, the end 83 of said bar is formed with an opening registering with a corresponding opening in the rear bar 65 and the interior of the upper boss 93 for the reception of the stud 95, said end 83 having its lower edge engaging the bracket 86 below the shoulder 91 thereof, and having its upper edge engaging the rear surface of the rear bar 65. A washer 93 is placed between the head of the stud 95 and the mounting bar end 83, and when the stud 95 is tightened in place, the mounting bar end 83, rear bar 65 and bracket 86 are firmly connected together.

The end 84 of the mounting bar 80 bears a like relationship to the end portion of the rear bar 65 and associated clamping structure.

It is to be noted that each bracket 86 and 88 extends to a considerable degree above the upper bar and below the lower bar so as to prevent the bumper of another car from riding over or under either of the bumper bars 64 and 65 and thus prevents interlocking of bumpers of adjacent vehicles.

In accordance with another form of the invention, a cup-like spacer bracket 99 is employed. This spacer is preferably of substantially elliptical cross section as clearly seen in Figure 16 and is preferably open at its rear end 100, its front end 101 being preferably closed except for a bolt hole 102. The bracket 99 is arranged to properly space apart adjacent portions of the front bar 103 and rear bar 104. It is desired that the spacers 99 extend directly rearwardly from the front bar, and consequently the ends 100 and 101 will be inclined to the axis of the spacer to a maximum extent longitudinally of the bars when such spacers are arranged at the ends of the bars, and to a smaller degree in accordance with the proximity of the spacer to the center of the bars. In addition to being inclined to the axis of the spacer in a direction parallel to the length of the bars, the ends 100 and 101 are inclined to the axis of the spacer in a direction transversely of the bars. In other words, the end surfaces of each spacer is formed to conform with and engage respectively the rear surface of the front bar 103 and the front surface of the rear bar 104. Thus the rear end 100 of the spacer is concave in both directions, and the front end 101 is convex in both directions.

The bolt hole 102 is arranged with its axis lying in a plane substantially normal to the portions of the bars 103 and 104 to be connected, said axis extending preferably horizontally. The front bar 103 is provided with a bolt opening formed to register with the bolt opening 102, and the rear bar 104 is formed with a bolt opening 105 which, when axially aligned with the bolt opening 102 in the spacer 99, is located within the confines of the open end 100. The bars and spacer are operatively assembled in the relationship shown in Figures 13 and 14, and receive the shank 106 of a clamping bolt 107 whose head 108 may have any desired configuration such as an oval. It will be clear, particularly upon inspection of Figure 14, that when the bumper structure is viewed from the front, the spacer 99 is entirely concealed, and only the bolt head 108 is visible.

Due to the inclination of the rear bar 104, a washer 109 having an inclined forward face 110 washer 109 having an inclined forward face 110 for engagement with the rear bar 104 is applied to the free end of the shank 106 and is provided with a rear face 111 which is substantially perpendicular to the axis of the washer. A lock washer 112 is applied to the face 111 and a nut 113 applied to the rear of the washer 112 and

tightened so as to rigidly clamp the parts together.

A further modified spacer bracket construction is shown in Figures 17, 18, 19 and 20. This structure includes the provision of a spacer 114 which when in assembled position is in the form of an inverted U-shaped member open at its rear end 115 and somewhat elongated and closed at its front end 116 except for a bolt hole 117.

For illustrative purposes, the front and rear bars 118 and 119, respectively, are illustrated as converging at their ends and spaced to a greater extent at their centers. However, it is to be understood that this is shown by way of example only, since as explained above the bars may be arranged in parallelism or any other desired relationship.

It is to be noted that the inner side wall 120 of the spacer 114 is cut away at 121 to provide clearance so that the bolt about to be described 20 may be easily manipulated. This cutout does not harmfully weaken the spacer and is provided on the inner side so as to be concealed from the end by the uncut outer wall 122. The front wall 116 is formed to conform to the rear surface of the 25 front bar 118, and the inverted U-shaped rear end 115 of the spacer is formed to conform to the front surface of the rear bar 119. The bumper bars may be mounted on the vehicle by any suitable means such as the mounting bar structure 30 of which a part is shown at 123. In such event, the outer end 124 of the mounting bar 123 is positioned in engagement with the rear surface of the portion of the rear bar 119 engaged by the rear end 115 of the spacer 114. Said end 124 35 and the front and rear bars 118 and 119, respectively, are formed with bolt holes adapted to be registered with the bolt hole 117 in the front wall 116 of the spacer 114. When thus assembled, said holes receive the shank 125 of a bolt 40 126 whose head 127 is inclined to the shank 125 so as to conform to the front surface of the front bar 118. The shank 125 preferably extends in substantial parallelism with the spacer 114, and is consequently inclined to the bars 118 and 119 45 and to the mounting bar end 124. In order that a clamping nut 128 and associated lock washer 129 may be properly applied to the threaded end of the shank 125 extending to the rear of the mounting bar end 124, there is provided a washer member 130 whose forward face 131 is inclined to the axis thereof so as to fit against the rear surface of the mounting bar end 124 as clearly seen in Figure 20. The rear face 132 of the washer member 130 is preferably normal to the axis thereof so as to be engaged by the washer 129 which in turn is engaged clampingly by the nut 128. When the nut 128 is tightened, the bars 118 and 119 are rigidly clamped to the spacer 114.

It will be appreciated that the spacing elements may be formed to have any desired shapes and yet function to properly assemble the bars.

The number of impact bars may be varied so that three or more may be employed in any desired arrangement within the scope of the invention, preferably in echelon as illustrated.

We are aware that many changes may be made and numerous details of construction may be varied through a wide range without departing from the principles of this invention, and we, therefore, do not purpose limiting the patent granted hereon otherwise than necessitated by the prior art.

We claim as our invention:

1. Bumper construction comprising resilient impact bars arranged in vertically lapped relation, rigid connecting means arranged between the bars so as to rigidly space apart and connect said bars, leaving the unconnected portions of the bars free to flex under impacts, and means for supporting the bumper construction from a vehicle through the first means. 5
2. Bumper construction comprising a connected pair of flexible impact bars arranged in echelon with their centers vertically lapped and horizontally spaced but closer together than their ends so as to reinforce the front bar against excessive flexure, and means connecting the bars together. 10
3. In an automobile including spaced bumper supporting members, a bumper construction comprising a pair of impact bars arranged in echelon so as to be vertically lapped intermediate their ends, and means connecting the intermediate parts of the bars together and formed to mount the bumper on said members. 15
4. Carrier or bumper structure comprising two impact bars spaced one ahead of the other throughout their length, means holding the bars spaced at their respective ends and securing the ends in the same horizontal plane against relative movement, said bars being cambered and being edge bent so as to vertically partially overlap intermediate their ends and present the appearance of a continuous comparatively wide impact surface when viewed from the front. 20
5. A bumper structure comprising impact bars spaced one ahead of the other throughout their length, means holding the bars spaced at their respective ends and securing the ends in the same horizontal plane against relative movement, said bars being edge bent and cambered so as to vertically overlap intermediate their ends with the rear bar projecting vertically above the front bar and with its upper edge in a 25
6. Carrier or bumper structure comprising two impact bars spaced one ahead of the other throughout their length, means holding the bars spaced at their respective ends and securing the ends in the same horizontal plane against relative movement, said bars being edge bent so as to vertically partially overlap intermediate their ends to present the appearance of a continuous comparatively wide impact surface when viewed from the front, and means intermediate the bar ends for securing said bars in such spaced and overlapped relation. 15
7. Carrier or bumper structure comprising two impact bars spaced one ahead of the other throughout their length, means holding the bars spaced at their respective ends and securing the ends in the same horizontal plane against relative movement, said bars being edge bent and cambered so as to vertically overlap intermediate their ends, and means intermediate the bar ends for securing said bars in such spaced and overlapped relation, said intermediate means being formed to mount the bumper structure on a vehicle. 20
8. A bumper structure comprising separate impact bars spaced one ahead of the other throughout their length, said bars being transversely inclined to lie in substantially parallel planes and being partially overlapped vertically whereby to present the appearance of a continuous comparatively wide impact surface when viewed from the front, and means for securing said bars in such spaced and overlapped relation and to a support. 30
